CLAIM

The ornamental design for a bicycle saddle, as shown and described.

DESCRIPTION

FIG. 1 is a front elevation view of a bicycle saddle showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view of a bicycle saddle showing my new design; and,

FIG. 8 is another perspective view thereof.

The long dashed broken lines shown on the top surface of the bicycle saddle illustrate stitching and form part of the claimed design. The broken line showing the bracket structures and other portions of the bicycle saddle do not form part of the claimed design.
